UNITED STATES PATENT OFFICE.

VICTOR BERGMAN, OF MYSIA, VICTORIA, ASSIGNOR OF ONE-HALF TO
WILLIAM GEORGE BOYLE, OF SAME PLACE.

FASTENING OR CLASP FOR BOOTS, &c.

SPECIFICATION forming part of Letters Patent No. 633,947, dated September 26, 1899.

Application filed November 12, 1898. Serial No. 696,265. (No model.)

To all whom it may concern:

Be it known that I, VICTOR BERGMAN, wheelwright, a subject of the Queen of the United Kingdom of Great Britain and Ireland, residing at Mysia, in the Colony of Victoria, have invented certain new and useful Improvements in Fastenings or Clasps for Boots and other Articles; and I do hereby declare that the following is a full, clear, and exact description thereof, which will enable others skilled in the art to which it appertains to make and use the same.

The object of this invention is to provide a fastening or clasp adapted to be attached to boots, gloves, corsets, or other articles and by which the wearer or user may draw the same together quickly and easily when required, the parts then retaining their closed position securely during ordinary use until purposely expanded.

In the present improvements no spring is necessary, and there is no loss of efficiency by use. The fact that the edges of the articles cannot always be conveniently brought to the same distance apart when closed is provided for by this invention and also the fact that it may be inconvenient to attach more than one or either of the edges referred to permanently to the fastening. To accomplish these objects, certain combinations of a series of links or plates which are hinged to one another, so as to fold into particular positions, are necessary, and a certain construction of the links themselves, as is next explained by reference to the attached drawings.

Figure 1 is a top plan view showing the clasp in its closed or fastened position, and Fig. 2 shows the same extended or opened.

E is a plate or link constituting the main member of the fastening and hereinafter called the "major" link. It is rigid and has hinged or pivoted to one end a side link or plate. (Shown by F.) The side link F, joining the apertured major link, is narrower than the latter, so as to pass through the same into the position shown in Fig. 1 when assuming the closed position, the side links in the said position having no liability to accidental un-

fastening, because they have passed considerably beyond or above a line which would connect the ends of the major link. In practice strains tending to draw apart the objects held by the fastening will, instead of tending to expand the closed fastening, simply cause the ends of the side links to press outwardly against the adjoining ends of the major link.

To make the fastening adjustable, the side link F has attached to it an end link H and staple I, engaging one of the eyes or slots J in bed-plate J³, which is affixed to the article; but what is more particularly claimed is having both side links adjustable, as hereinafter described. One adjustment is to suitably locate a staple, as I', relatively to a bed-plate, as J', at the time of purchase, the inner ends of the staple being kept from injuring the wearer by the tongue of the shoe or by other means when employed for other purposes, the purpose of such an adjustment being to allow a larger limit of adjustment in fitting, future adjustment being effected by means of the staple I and the slots J⁴ in the fastening J³.

The bed-plate J has, besides the functions above indicated, another important function. By causing the edge J² of the bed-plate to project from its junction with the major link some distance under the latter—that is to say, so that when the side link F is folded in the edge J² will come below the end F—the effect is that the bed-plate, having one end J² arranged as aforesaid and the other end J³ attached to an object to be fastened, will in practice keep the fastening in closed position in spite of forces that would expand the fastening if unprovided with such an arrangement.

Having thus described my invention, what I claim as new, and desire to secure by Letters Patent of the United States, is—

In a clasp for shoes and the like, the combination with a main link E, pivotally connected to the adjustable fastening J' upon one side, and pivotally connected upon the other end to the link F, which is adapted to pass through the link E, said link F being

pivottally connected to the smaller link II, which is adjustably connected to the stationary fastening J⁵ by means of the staple I, the said links folding together and holding the 5 fastenings J¹, J⁵ in a locked position, substantially as described.

In witness whereof I have hereunto signed

my name, this 1st day of September, 1898, in the presence of two subscribing witnesses.

VICTOR BERGMAN.
